(57) **CLAIM**

The ornamental design for a display screen or portion thereof with graphical user interface, as shown and described.

DESCRIPTION

FIG. 1 is a front view of a display screen or portion thereof with graphical user interface in accordance with a first embodiment, showing our new design; and,

FIG. 2 is a front view of a second embodiment thereof. The outer perimeter broken line in the drawings represents a display screen or portion thereof and forms no part of the claimed design. The remaining broken lines in the drawings illustrate portions of a graphical user interface that form no part of the claimed design.

1 Claim, 2 Drawing Sheets
